PATTERN MECHANISM FOR THE MANUFACTURE OF LACE PATTERNS

Johannes Lorenz, Chemnitz, Germany; vested in
the Alien Property CustodianApplication May 31, 1939, Serial No. 276,699
In Germany May 31, 1938

7 Claims. (Cl. 66—96)

The present invention relates to flat rib knitting machines provided with a jacquard wrap pattern mechanism for the manufacture of lace patterns.

Hitherto lace patterns have been produced on flat rib knitting machines by tickling on individual loops of a row of needles by lace points arranged according to pattern and by tickling off such loops upon the adjacent needles. Thereby only a certain possibility of patterning is obtained.

By means of the present invention the production of lace patterns distributed according to jacquard patterns is possible at desired points of a row of loops. This is obtained by the fact that by means of a jacquard mechanism, already present for the wrap guides, lace points are brought into the range of the heads of the needles of a row of needles or withdrawn out of this range, whereby jacquard lace patterns or jacquard wrap patterns or ordinarily jacquard lace and jacquard wrap patterns are formed on the corresponding needles in one row of needles.

It is already known to shiftable mount the jacquard roller in such a manner as to be capable of being moved in two positions of height in the direction of the guides to be moved and at right angles to these, thereby allowing the jacquard roller to selectively act upon one or the other group of guides or points. According to the invention, the jacquard mechanism moved in the position for acting upon the lace points then performs a selecting motion only relatively to the lace points, while all other movements required are performed by a frame carrying the lace points only.

In the accompanying drawings one construction according to the invention is shown by way of example.

In these drawings:

Figure 1 shows the position of rest of the wrap guides.

Figure 2 is the wrap position of the wrap guides.

Figure 3 shows the position of the lace points, after actuation of the jacquard roller.

Figure 4 shows the same operative position of the lace points after lowering into the lace transferring position.

Figure 5 represents the tickling on position of the lace points.

Figure 6 shows a plan view of a portion of a jacquard card having two rows of perforations.

Figure 7 illustrates a plan view of a portion of a jacquard card provided with three rows of perforations.

Figure 8 is a view partly in section of the device according to the invention.

Figure 9 is a plan view of the invention.

Figure 10 is an elevation of the device according to the invention, and

Figure 11 is a view similar to that illustrated in Fig. 8 but showing the individual members in a different position.

In the machine illustrated the frame needles 1 (Fig. 9), the rib needles 2 of which in practice there is a plurality, the jack sinkers 3 of which in practice there is also a plurality, the general presser 4, and the knocking over bits 5 of which, finally, there is also a plurality in practice, are arranged in the usual manner.

The wrap guides 17 are arranged in a known manner in a head carrying a head rail 15 of a frame 16. Only one group of wrap guides 17, or several groups, as indicated for instance in the drawings, may be provided. In guides 18, swingably mounted upon a shaft 44 journaled in the rear portion of the frame 16, arms 19 are shiftable arranged carrying a frame 20 in which lace points 9 (Fig. 9) are individually movably arranged in guides 21 and held in these guides by covering rails 21'.

In the machine frame, moreover, a shaft 22 is mounted carrying double-armed levers 23, 24. Links 25 (Figs. 2 and 8), actuated in the usual manner by means of a cam device (not shown), are connected to the lever arms 23. The lever arms 24 carry rollers 26 cooperating with stop plates 27 provided on the arms 19. By means of springs 28 connected on the one hand to the guides 18 and on the other hand to the arms 19, the stop plates 27 are pressed against the rollers 26 of the levers 24. Fixed upon the rear covering rails 21' of the guides 21 are leaf-springs 29, carrying a safety rail 30. The latter is provided

with a projection extending rearwardly as an inclined surface 31 and forming a shoulder 32 at the front end. In the head rail 15 of the frame 16 releasing members 33 for the safety rail 30 are fixed, the ends of which have an inclined surface at the side facing the frame needles 1 (Fig. 1). On the frame 20 carrying the lace points 9 guide rollers 35 are mounted in downwardly directed arms 34. The rollers 35 are guided upon races 36 fixed upon the head rail 15 of the frame 16. The races are provided with trough-shaped recesses 37. By means of springs 38 the ends of which are connected to the frame 20 and the frame 16 respectively, the guide rollers 35 are drawn against the races 36. A displace-

able rail 10 cooperates with the projections 8 of the lace points 9.

Mounted at suitable frame members are guide members 60 which serve to guide a lifting slide 61 carrying the bolt 62 and the slide 63. By means of a cam this lifting slide 61 is moved in an upward and downward direction as required. Displaceably mounted upon the bolt 62 and the slide 63 is the guide head bearing 64. The bearing 64 is guided by means of screws 65 and 66 (Fig. 8). For safety purposes the bolt 64' is provided. The guide head bearing 64 carries the head rail 15 as well as the roller sliding bearing 67 which latter is guided by the lifting rod 68 in the guide head bearing 64. To prevent an undesired rotation of the sliding bearing 67 a bolt 69 is provided. Guided in the sliding bearing 67 is a cube bearing 70 carrying the jacquard roller 40. The cube bearing 70 is provided with an extension 70' carrying a pin 71 which is hingedly connected to an arm 73 of a double-armed lever 73, 76, by means of a link 72. The double-armed lever 73, 76 is mounted upon a shaft 74 which may be rotated as required by the main cam shaft (not shown) of the machine by means of a link 75 and the arm 76 of the double-armed lever 73, 76.

If normal jacquard wrap patterns are to be produced, the sliding bearing 67 occupies the position shown in Fig. 8. If, however, jacquard lace patterns are to be produced the lifting rod 68 is raised by means of a cam (not shown), so that the jacquard roller 40, if moved forwardly, actuates the lace points 9, as shown in Fig. 11.

From Fig. 9 it may be gathered, that the lace points 9 are arranged opposite the frame needles 1 across the entire width of the division. After selecting the lace points 9 to be operated by means of a jacquard card 41, made for this purpose, the corresponding loop is covered and transferred as soon as the jacquard roller 40 is moved.

Besides the above described roller bearings 67, 68, 69 and 70 the frame 16 is mounted upon the head rail 15. The frame 16 in turn carries the bearing 16' and the guide 18 rotatably mounted on the shaft 44. In the guide 18 again arms 19 are displaceably mounted which carry the frame 20 with the guides 21 and the cover rails 21'.

To release the lace points 9 to be operated and to return the latter a bent rail 77 provided with two pins 78, 78' (Fig. 8), is connected to the rail 10 at both ends of the same. If the jacquard roller 40 in its upper operating position shown in Fig. 11 is shifted, the shaft 39 strikes against the pin 78 and releases the lace points before the jacquard card reaches these lace points. If now the jacquard roller 40 is returned the pin 78' is engaged and shifted by the shaft 39 and all the lace points are returned into their normal position.

Each card 41 of the jacquard mechanism is provided with perforations corresponding to the pattern to be produced. If the wrap guides and the lace points are operated without feeding the jacquard card two rows of perforations 42 (Fig. 6) are required for the wrap guides and the lace points if only one group of wrap guides is present. If, however, as has been assumed in the example shown in the drawings two groups of wrap guides are present, three rows of perforations 43 (Fig. 7) are required in each jacquard card.

In Fig. 1 the individual parts are shown in their position of rest. By moving the jacquard

roller 40 forwardly in the lower horizontal plane in the direction of the arrow x (Fig. 2) the wrap guides required for the patternings are in the usual manner advanced from their position of rest, whereby they are lifted. After further lifting and lateral shifting of the whole mechanism (Fig. 2), the selected wrap guides 17 in a known manner place their thread around the oppositely situated frame needles 1. During the production 10 of wrap patterns, the lace points 9 remain in their position of rest.

If lace patterns are to be produced by the lace points 9, the whole mechanism is lifted in such a manner that the lace points 9 when advanced are moved over the frame needles 1. From its position of rest the jacquard roller 40 is in the manner described above lifted upwardly in a vertical plane in the direction of the arrow y (Fig. 3) and then advanced against the lace points 9 in the upper horizontal plane in the direction of the arrow z. As far as no perforations are present in the jacquard card, the lace points are advanced and shifted over the hooks of the frame needles (Fig. 3).

25 The jacquard roller 40 performs a single selecting movement only towards the lace points. All other movements required are solely effected by the frame 20 carrying the lace points 9.

The frame 20 is usually held in the position 30 shown in Fig. 3 by the arm 24 of the double-armed lever 23, 24. The stop plate 27 is situated opposite the guide 18 in the position indicated at E. The guide roller 35 bears against the portion of the race 36 lying behind the trough-like 35 recess 37. The point of the projection of the safety rail 30 rests upon the releasing part 33, so that shifting of the rail 10 as far as to the front covering rail 21' is not impeded (Fig. 3).

To bring the lace points into the lace transferring position, the double-armed lever 23, 24 40 is swung by means of the link 25 actuated by the cam device to shift the arms 19, as may be seen from Fig. 4, into the position F (Fig. 3) without changing the position of the frame 16. By this movement the safety rail 30 slides off the releasing part 33 and leaf springs 29 cause the shoulders 32 of the safety rail 30 to engage behind the projections 8 of the advanced lace points 9, so that the selected lace points are secured in 50 position. Simultaneously the guide rollers 35 are moved into the trough-shaped recesses 37 so that under the action of the springs 38 the frame 20 is swung around the axis of the shaft 44, whereby the advanced lace points come into the lace transferring position.

If the shifting of the arms 19 into the position 55 G (Fig. 3) is continued the guide rollers 35 leave the trough-shaped recess 37 and run upon the portion of the race 36 situated in front of the recess 37. The frame 20 hereby again is swung around the axis of the shaft 44 so that the lace points 9 come into the tickling off position (Fig. 5).

If the double-armed levers are returned again 60 into their position of rest by the cam device the springs 28 connected to the arms 19 draw the frame 20 back into its position of rest. By the inclined surface 31 of the safety rail 30 abutting against the inclined surface of the releasing portions 33, the leaf spring together with the safety rail is pressed upwardly and held again in the lifted position by the releasing portion 33 so that the safety rail 30 releases the projections 8 of the lace points and the rail 10 then may return again 65 the advanced lace points into their position of rest (Fig. 1).

It is evident that the movements for taking up and taking off loops also may be effected by lifting and lowering the entire jacquard mechanism. During the vertical movement of the jacquard roller 40 or movement in the direction as is indicated by the arrow y in Fig. 3 it may also be rotated whereby the required jacquard card carried thereby may be selected or adjusted and the perforations of the so adjusted or selected card placed in their proper positions.

What I claim is:

1. A flat rib knitting machine comprising a row of needles, lace points, a jacquard roller forming part of a jacquard mechanism mounted and actuated for performing a selecting movements towards said lace points, and a frame carrying said lace points movably mounted on said jacquard mechanism.

2. A flat rib knitting machine comprising a row of needles, lace points, wrap guides, a jacquard roller forming part of a jacquard mechanism adapted to be moved in various vertical positions in a direction towards the wrap guides and said lace points respectively and at right angles for selectively acting upon said wrap guides and said lace points only, a frame carrying said lace points movably mounted in said jacquard mechanism, a shaft carried by the rear portion of said frame having guides pivotally mounted thereon, and a second frame slidably arranged in said guides and having guides of which said lace points are individually movable.

3. A flat rib knitting machine comprising a row of needles, lace points, wrap guides, a jacquard roller forming part of a jacquard mechanism adapted to be moved in various vertical positions in a direction towards said wrap guides and said lace points respectively and at right angles to these for the purpose of selectively acting upon said wrap guides and said lace points only, a frame carrying said lace points movably mounted in said jacquard mechanism, a shaft carried by the rear portion of said frame, guides pivotally mounted on said shaft, a second frame carried by said guides and having guides in which said lace points are individually movable, and jacquard cards carried by said jacquard mechanism whereby when the latter is moved to one position said wrap guides will be actuated and when moved to another position said lace points will be operated.

4. A flat rib knitting machine comprising a row of needles, lace points, wrap guides and a jacquard roller forming part of a jacquard mechanism adapted to be moved in various vertical positions in a direction towards said wrap guides and said lace points respectively and at right angles to these for the purpose of selectively acting upon said wrap guides or said lace points only, a frame carrying said lace points movably mounted on said jacquard mechanism, a shaft supported by the rear portion of said frame upon which guides are pivotally arranged, a second frame carried by said guides having guides in which said lace points are individually movable, and means for adjusting said second frame carrying said lace points.

5. A flat rib knitting machine as set forth in claim 4, in which a double-armed lever is mounted for acting upon arms on which said frame is mounted.

6. A flat rib knitting machine as set forth in claim 4, in which said second frame is by means of a downwardly inclined arm carrying a guide roller guided upon a race of said frame carrying said lace point guides and provided with a trough-shaped recess.

7. A flat rib knitting machine comprising a row of needles, lace points, wrap guides and a jacquard roller forming part of a jacquard mechanism adapted to be moved in various vertical positions in a direction towards said wrap guides and said lace points respectively and at right angles to these for the purpose of selectively acting upon said wrap guides or said lace points only, a frame carrying said lace points movably mounted on said jacquard mechanism, a shaft supported by the rear portion of said frame upon which guides are pivotally arranged, a second frame carried by said pivotally arranged guides having guides in which said lace points are individually movable, a spring-actuated safety rail adapted at times to engage said lace points for limiting their movement within the guides therefore, a releasing member for moving said safety rail out of engagement with said lace points, actuating arms mounted in said second frame, a double-armed lever for moving said arms in one direction, and spring-actuated means for moving said arms in an opposite direction.

JOHANNES LORENZ.
